UNITED STATES PATENT OFFICE.

JAMES L. KOPLIN, OF ROCKFORD, ILLINOIS.

ROTARY COAL-SIFTER.

SPECIFICATION forming part of Letters Patent No. 224,341, dated February 10, 1880.

Application filed October 30, 1879.

To all whom it may concern:

Be it known that I, JAMES L. KOPLIN, of the city of Rockford, in the county of Winnebago and State of Illinois, have invented a new and useful Improvement in Rotary Coal-Sifters, of which the following is a specification.

This invention relates to that class of rotary coal-sifters employed mainly in domestic practice to separate the unburned particles of coal from the ashes after they have passed through the stove.

The object of this invention is to provide a rotary coal-sifter of a convenient cabinet form, capable of use in dwellings or inclosed compartments, to separate the unburned particles of coal from the ashes after they have passed from the stove or furnace, and to confine the dust within the cabinet, to accomplish which I have designed and constructed the cabinet-screen represented in the accompanying drawings, in which—

Figure 1 is an isometrical representation of my improved cabinet-screen, in which portions of the casings are broken away to reveal the internal structure. Fig. 2 is a vertical section, cutting the screen at right angles.

In the figures, A represents the sides, and B the bottom, joined to each other, forming a rectangular casing of box form, and in this instance of greater height than width, and is fitted with a hinged close-fitting lid, C. This casing forms the outer walls of my improved cabinet-screen.

At D is represented a revolving screen consisting of heads a, mounted on a central shaft, b, which has its bearings in the sides of the cabinet toward its upper end. The heads a are separated a proper distance, in which position they are fixed to the shaft, and are relatively fixed to each other by means of ribs c, fixed to their peripheries at proper intervals, producing a reel of suitable size to revolve within the cabinet. A suitable division of this reel, as at E, is hinged in place, forming a door opening into the reel, and is fitted with a button, d, pivoted to the reel, capable of being turned to overlap the free edge of the hinged door, to hold it in its closed position, and that may also be turned to permit the door to swing open. This reel, including the

hinged door, is covered with a suitable wire-screen webbing, F, to permit the ashes and fine particles to pass through it, and retain the larger particles of unburned coal.

The door, when opened upward, as represented in dotted lines, Fig. 2, may be hooked on the pin e, fixed in the case, which will serve to hold the screen in position to receive the coal and ashes to be separated.

G represents a hand-crank fixed to the outwardly-projecting end of the screen-shaft, by means of which the screen may be made to rotate. H represents a hand-lever pivoted at its lower end to the casing, and its free end rising to a convenient height near the top of the cabinet.

At f is represented a trip-stop with enlarged inner end, having its shank passed outward through the casing and pivoted to the hand-lever H, and is provided with a spiral spring, g, surrounding its shank portion, between the casing and the lever, which operates to hold the shoulders of the stop pressed against the inner surface of the casing. This trip-stop is placed in the plane of travel of the button d, in such a manner that when the hand-lever H is moved to the position represented in the dotted lines the stop will be moved inward, as shown in dotted lines, which, in the revolutions of the screen, will engage the pivoted button and cause it to turn from the hinged door, and permit it to drop into the position shown in dotted lines at h, which will permit the contents of the screen to be discharged through the opening of the door.

I represents boards placed in the lower portion of the cabinet lengthwise with the screen, inclined toward the center, forming hopper-like sides, which serve to conduct the discharged contents of the screen toward the center of the cabinet.

K represents a valve placed lengthwise of the screen, pivoted at its ends toward its lower edge centrally in the sides of the cabinet at the point at which the inclined hopper sides would meet if produced. One of the pivots of this valve extends through the side of the cabinet, and is fitted with a lever-arm, L, by means of which the valve K may be changed from its position in solid lines to the position represented in dotted lines, and in each posi-

tion will form an even upper surface with the inclined hopper sides to conduct the screenings or discharged contents of the screen to the drawers designed to receive them.

5 O and P represent drawers of the usual form, fitted to slide into the cabinet lengthwise of the screen, one on each side, below the valve, and are designed to receive the contents of the screen as separated.

10 m represents inclined plates fixed to the inside of the casing to conduct the screenings and discharged contents of the screen into the drawers.

15 n represents a button pivoted between the outer ends of the drawers, adapted to overlap the drawers to prevent their accidental displacement.

From the foregoing it will be seen that the hinged lid of the cabinet being raised, and the 20 screen opened, as represented in dotted lines, the ashes to be screened may be deposited in the screen, and the door closed and fixed by means of the button. The lid of the cabinet may then be shut, after which the screen may. 25 be revolved by means of the crank-handle, which rotation will cause the contents of the screen to be separated, and the ashes and smaller particles passing through the meshes of the screen will descend the inclined hopper 30 sides over the valve into one of the drawers, and when sufficiently screened the valve may be changed to the opposite side by means of

lever-arm L; then, by means of the hand-lever H, the trip-stop f may be pushed in, and the further revolution of the screen will bring 35 the button d in contact with the trip-stop, which will cause it to be turned off from the door and permit it to open, and the contents of the screen to be discharged onto the inclined hopper sides and conducted over the valve 40 into the drawer on the opposite side from the ashes. The drawers can then be withdrawn, and their contents disposed of as may be convenient.

By the use of my improved screen I am enabled 45 to separate the ashes from the unburned coal, and confine the dust in the cabinet.

I claim as my invention—

1. The combination, with the revolving screen having a hinged section, and a button 50 for securing it in a closed position, of a spring-pressed trip-stop, arranged to unlock the button when the screen is revolved and discharge the contents of the screen, substantially as set forth.

2. The combination, with a revolving screen and a trip-stop, of inclined hopper sides to conduct the screenings and discharged contents of the screen into suitable receptacles, substantially as hereinbefore set forth.

JAMES L. KOPLIN.
